BUFFET

Ernest Herrmann, South Norwalk, Conn., assignor to Heywood-Wakefield Company, Gardner, Mass., a corporation of Massachusetts

Application September 13, 1957, Serial No. 47,722

Term of patent 3½ years

(Cl. D33—6)

Fig. 1 is a front perspective view of a buffet showing my new design;

Fig. 2 is a fragmentary perspective view partly in section, of the leg and adjacent portions of the front left corner of Fig. 1, but on an enlarged scale;

Fig. 3 is a perspective view of one of the legs alone as viewed slightly downwardly and substantially on the scale of Fig. 2;

Fig. 4 is a detailed fragmentary sectional view on the line 4-4 of Fig. 2, but on a larger scale; and

Fig. 5 is a sectional view on the line 5-5 of Fig. 2 on the scale of Fig. 4.

The side not shown is like the side shown while the back aside from the legs is plain and unornamented.

The dominant features of the design reside in the portions shown in full lines on the drawing.

I claim:

The ornamental design for a buffet, substantially as shown and described.
